UNITED STATES PATENT OFFICE.

J. C. FRIEDRICH PAGEL, OF DETROIT, MICHIGAN.

SLEIGH.

SPECIFICATION forming part of Letters Patent No. 248,841, dated October 18, 1881.

Application filed August 9, 1881. (No model.)

To all whom it may concern:

Be it known that I, J. C. FRIEDRICH PAGEL, of Detroit, in the county of Wayne and State of Michigan, have invented an Improvement 5 in Sleighs, of which the following is a specification.

The nature of this invention relates to certain new and useful improvements in the construction of sleighs of that class denominated 10 "swell-body cutters;" and the invention consists in the peculiar construction, arrangement, and combinations of the parts, all as more fully hereinafter set forth.

Figure 1 is a perspective view. Fig. 2 is a 15 plan view, from the bottom, of the rear portion of the body.

In the accompanying drawings, which form a part of this specification, A represents a strip or piece of timber cut into the desired form, 20 and bent into shape so as to form the back a and bottom b and body-rave c, formed and bent from one piece, to the front end of which is secured the dash B.

C represents the broad arms, which are 25 formed and bent from one piece of wood, being cut away to form the bead d at the back.

D represents the lower arm-rails, which are secured to place in the ordinary way to the rave c and broad arm.

E represents the arm-panels, surmounted by 30 the top arm-rail, F. The panels E and those between the rail D and bottom b are inserted in the ordinary manner.

By this construction and arrangement of parts I construct a sleigh which is much 35 stronger than those wherein the back and bottom are in separate pieces, and yet which is cheaper to build.

What I claim as my invention is—

1. A sleigh wherein the back, bottom, and 40 body-raves are formed from one continuous piece, A, substantially as set forth.

2. A sleigh wherein the back, bottom, and body-raves are formed from one piece, in combination with the broad arms C, also formed 45 from one piece, substantially as specified.

That the above is my invention I hereby affix my signature this 20th day of July, 1881.

J. C. FRIEDRICH PAGEL.

In presence of—

H. S. SPRAGUE,
E. SCULLY.
